UNITED STATES PATENT OFFICE.

LAURITZ W. ANDERSEN, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

DESIGN FOR A CEILING-PLATE.

41,387.

Specification for Design.

Patented May 16, 1911.

Application filed March 9, 1911. Serial No. 613,477. Term of patent 3½ years.

To all whom it may concern:

Be it known that I, LAURITZ W. ANDERSEN, a citizen of the United States, residing at Waterbury, in the county of New Haven and State of Connecticut, have invented a new, original, and ornamental Design for Ceiling-Plates, of which the following is a specification, reference being had to the accompanying drawing, forming part thereof.

The figure is a perspective view of a ceiling plate, showing my new design.

I claim:

The ornamental design for a ceiling plate, as shown.

LAURITZ W. ANDERSEN.

Witnesses:

A. J. STORZ,

C. W. NORTHRUP.
